UNITED STATES PATENT OFFICE.

HENRY C. WALDMANN, OF WAPAKONETA, OHIO.

PIGEON-TRAP.

Specification of Letters Patent. Patented Jan. 28, 1913.

1,051,470.

Application filed March 12, 1912. Serial No. 683,211.

To all whom it may concern:

Be it known that I, HENRY C. WALDMANN, a citizen of the United States, residing at Wapakoneta, in the county of Auglaize and State of Ohio, have invented certain new and useful Improvements in Pigeon-Traps, of which the following is a specification.

This invention relates to improvements in pigeon traps or devices adapted to throw targets into the air, and the object is to provide a device by which targets may be shot rapidly into the air.

With the above and other objects in view, which will be clearly described in the following specification and more specifically pointed out in the appended claims, I have invented the device illustrated in the accompanying drawings in which—

Figure 1 is a side elevational view of my improved trap; Fig. 2 is a detail elevational view of a spring tension member; Fig. 3 is a longitudinal sectional vertical view showing the trap setting mechanism; Fig. 4 is a detail perspective view of a catch and release mechanism; Fig. 5 is a perspective view of a table for supporting the trap; Fig. 6 is a perspective view of a shoot; and Fig. 7 is an elevational view of a trap setting and releasing mechanism.

Like reference characters indicate like parts throughout the specification and in the several views in the drawings, in which 1 indicates a table provided with pointed legs 2 which have a horizontal portion 3 extending beyond the table whereby said pointed legs may be driven into the ground. Bolted to the table 1 is a member 4 to which is pivoted by means of a shaft 5 a tension member 6 having an arm 7. Secured to the member 6 is the end 8 of the clock spring member 9 having an elongated spring arm 10 on the free squared end of which is provided a cup 11 which is adapted to be drawn down by the chain 12 to seat on the upper edge of the casing 13 adjacent the outlet 14 which is an integral part of said casing, the end 15^a of the shoot 15 is adapted to seat within said member 14 and be held there by forks 15^b or any other suitable means. The outer end of the shoot 15 is supported by the legs 16. Secured to the member 13 is a pair of opposing standards 18 and 19 which are connected at the top by the portion 20 and to the upper end of 55 which is secured the spring 21. The arm 10 is slidable between said standards 18 and 19

and when released by the catch 22, which is adapted to engage said squared portion 17, will be thrown up between said standards by means of the tension of the spring 9 and 60 will engage the spring 21 and be suddenly stopped thereby and thus project the ball 23 into the air, as shown in Fig. 1 in dotted lines 23^a and 11^a.

The chain 12 is secured to the arm 10 and 65 passes into the casing 13 and over the pulley 24 and out rearwardly of the table 1 and is connected by means of the cable 25 to the lower end of the lever 26 which is pivoted at 27 to the standard 28 which is adapted 70 to be driven into the ground at some considerable distance from the table 1 and is more securely supported in a vertical position by means of the leg 29. Secured to the inner portion of the casing is a coil 75 spring 30 which encircles the chain 12 and is secured thereto at 31 whereby said chain when released by the movement of the lever 26, the slack of said chain will be drawn rapidly toward the arm 10 whereby said lever will be free to move upward as soon as the catch 22 is released. The manner of releasing said catch being as follows: Secured to the standard 28 is a bracket 32, 80 upon the outer end of which is pivotally 85 mounted a lever 33 to the lower end of which is secured a cable 34, the free end of which is secured at 35 to a crank member 36, the end 37 of which presses against the lower portion 38 of the catch 22, said catch 90 being pivoted to the bracket 39 and being pressed normally toward said arm 10 by means of the spring 40. When the lever 26 is drawn in the inclined direction as 95 shown in dotted lines 41 in Fig. 7 the portion 42 of said lever abuts the curved portion 43 of said lever 33 and draws the end 44 of said lever toward said standard 28 whereby the cable 34 draws the arm 45 in such a direction that the arm 37 of said 100 lever will press against the portion 38 of said catch member 22, and draw said catch member 22 out of connection with the said portion 17, as shown in dotted lines 46 in Fig. 4, whereby said arm 10 will be released 105 in order to project a pigeon or target into the air.

On the table 1 are provided U-shaped members 47 and 48 which are adapted to hold the sections of the shoot 15 when not in use. Secured to the member 4 is a bracket 49 which is provided with a screw-

threaded opening through which the thumb screw 50 is adapted to screw whereby it will abut the arm 7 of the spring holding member 6 by means of which the tension of 5 said spring may be rapidly regulated. The opposing walls of the casing 13 are provided with channels 51 into which a member 52 is adapted to slide. This member 52 is provided with a right-angular projection 10 53 which is engaged by a spring member 54 secured at 55 to said casing, this spring adapted to normally hold said member 52 in a raised position as shown in Fig. 3 whereby balls contained in the shoot 15 are 15 prevented from rolling therefrom when the cup 11 is in a raised position. When this cup is lowered it seats upon the member 53 and presses the member 52 down into the casing whereby the cup is in a position to 20 raise one of the balls from the shoot 15. It will be seen that by throwing the lever 26 to a vertical position, as shown in full lines in Fig. 7, the chain 12 will draw the arm 10 down to a position where it will be 25 engaged by the catch 22 so that the cup 11 will receive a ball from the shoot 15, and when said lever 26 will be drawn in the position shown by the dotted lines 41 in said 30 Fig. 7 the portion 42 of the lever 26 will trip the lever 33 so that the catch 22 will be released as heretofore explained and a target will thus be projected into the air.

Having now described my invention that 35 which I claim to be new and desire to procure by Letters Patent is:

1. A device of the character described consisting of a spring arm having a cup thereon and a ball shoot adapted to deliver the ball into said cup and means whereby

said cup may project said ball into the air, 40 said means consisting of a clock spring of which said arm is an integral part, a guide for said arm, a resilient stop for said arm, means for holding said arm in a lowered position, said means consisting of a spring 45 actuated catch, means for tripping said catch whereby said arm will be released, said means consisting of a lever operated crank lever, and means for lowering said spring arm, said means consisting of a 50 cable, a lever adapted to actuate said cable, said lever adapted to trip said catch.

2. A device of the character described consisting of a spring arm having a cup thereon and a ball shoot adapted to deliver 55 the ball into said cup and means whereby said cup may project said ball into the air, said means consisting of a clock spring of which said arm is an integral part, a guide for said arm, a resilient stop for said arm, 60 means for holding said arm in a lowered position, said means consisting of a spring actuated catch, means for tripping said catch whereby said arm will be released, said means consisting of a lever operated 65 crank lever, and means for lowering said spring arm, said means consisting of a cable, a lever adapted to actuate said cable, said lever adapted to trip said catch and automatic means for controlling the movement 70 of the balls in said shoot.

In testimony whereof I affix my signature in presence of two witnesses.

HENRY C. WALDMANN.
